Primary Examiner — Steven J Czyz

(57) **CLAIM**

The ornamental design for a pill organizer, as shown and described.

DESCRIPTION

FIG. 1 is a perspective view of a pill organizer showing my new design;

FIG. 2 is an alternative perspective view of a pill organizer with the cases in open status;

FIG. 3 is another perspective view of a pill organizer with the cases in open status;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines show features of the pill organizer that form no part of the claimed design.

1 Claim, 9 Drawing Sheets# US D1,010,306 S
